DESIGN FOR A RELISH TRAY OR SIMILAR ARTICLE

Robert A. Kelly, East Pittsburgh, Pa., assignor to United States Glass Company, Pittsburgh, Pa.,
a corporation of Pennsylvania

Application November 11, 1937, Serial No. 72,786

Term of patent 3½ years

To all whom it may concern:

Be it known that I, Robert A. Kelly, a citizen of the United States, residing at East Pittsburgh, county of Allegheny, in the State of Pennsylvania, have invented a new, original, and ornamental Design for a Relish Tray or Similar Article, of which the following is a specification, reference being had to the accompanying drawing, forming a part thereof, in which—

Figure 1 is a fragmentary top plan view of a relish tray showing my new design, it being understood that the remainder is substantially identical with the part shown;

Figure 3 is a bottom plan view of half of the relish tray showing my new design, it being understood that the other half is substantially identical with the half shown.

I claim:

The ornamental design for a relish tray or similar article, substantially as shown and described,

ROBERT A. KELLY.
